M. C. HENLEY.

AUTOMATIC OIL DRIP CATCHER.

APPLICATION FILED APR. 26, 1920.

1,382,782.

Patented June 28, 1921.

UNITED STATES PATENT OFFICE.

MICAJAH C. HENLEY, OF RICHMOND, INDIANA.

AUTOMATIC OIL-DRIP CATCHER.

1,382,782.

Specification of Letters Patent. Patented June 28, 1921.

Application filed April 26, 1920. Serial No. 376,572.

To all whom it may concern:

Be it known that I, MICAJAH C. HENLEY, a citizen of the United States, residing in the city of Richmond, in the county of Wayne, 5 State of Indiana, have invented a new and useful Automatic Oil-Drip Catcher, of which the following is a full, clear, and comprehensive specification and exposition, the same being such as will enable others to make and 10 use the same with exactitude.

In the operation of oil pumps, or dispensers, for supplying motor vehicles, it is well known that each time oil is drawn there is considerable drippage of oil from the nozzle 15 of the pump, or dispenser, and this results in a considerable waste of oil, and oil accumulates on the floor or base resulting in the oil being tracked over the surrounding floor or walk and into vehicles, also the wind frequently 20 blows the dripping oil onto one's clothing, and it otherwise causes a very unsightly appearance and results in more or less damage. Therefore to overcome the above mentioned objectionable features, and 25 to save the oil for useful purposes, is the primal object of this invention.

Broadly speaking, my object is to provide an automatic oil drip catcher for either inside or outside dispensaries which will be 30 neat and attractive in appearance, strong and durable in construction, easily operated and controlled, positive in action, adapted to save considerable oil, and which can be manufactured and sold at a comparative low price.

Other objects and particular advantages 35 of my present invention will suggest themselves in the course of the following description, and that which is new will be correlated in the appended claims.

The preferred means for carrying out my 40 invention in a practical and efficient manner is shown in the accompanying drawings, in which Figure 1 is a side elevation of my construction, showing the same in operative position in connection with an oil pump or dispenser. Fig. 2 is a top plan view of the device alone. Fig. 3 is a cross section of the device, as taken on the line 3—3 of Fig. 1. Fig. 4 is a vertical central section of the head 45 or upper portion of the device. Fig. 5 is an elevation of lower portion of the back or rear of the device. And Fig. 6 is a plan view of the two supporting lugs.

Similar indices denote like parts throughout the several views.

In order that the construction, the opera-

tion, and the advantages of the invention may be more fully understood and appreciated, I will now take up a detailed description thereof, in which I will set forth the several features as fully and as comprehensively as I may.

Referring now to the drawings in detail: Letter A denotes a base, which may be a floor, curb, or sidewalk, to the surface of 65 which the pump may be secured. Letter B denotes the base portion of the pump which may be secured on the base A by means of a plurality of bolts C which extend upward from the base A in which they are secured 70 and on which bolts are run the nuts D by which the base B is secured in position. Letter E denotes the body of the pump which carries the faucet F which is adapted to cut off the flow of oil by means of the handle 75 G. Said faucet has a downwardly extending nozzle H through which oil is conducted to a vessel. The said pump may be operated by the crank I. However the construction 80 of the pump is immaterial to this invention as other means may be employed to cause the oil to flow through the nozzle H.

The invention comprises the container including the two sides 1 and 2, the front 3, the back 4, and the bottom 5, thereby providing means for holding the oil; said container flares forward from the bottom to the top. Secured to the back 4 and extending down even with the bottom 5 is the triangular plate 6 whose lower corners project 90 outward beyond and at right-angles to the sides 1 and 2.

Carried by and extending down from the lower corners of the plate 6 are the two, 95 spaced apart, vertical pivots 7 and 8.

Formed integral with the body of the container just described is a head portion which is formed by projecting upwardly the sides 1 and 2 and the back 4, and then extending the said projections forward to form the 100 sides 9 and 10 of the head, and the sides 9 and 10 are connected at their front ends by the member 11. A head-top 12 connects the projecting upper edges of the members 1, 2, 4, 9, 10 and 11. A slot-like aperture 13 is 105 formed through the forward portion of the top 12, the same being of a width such as to receive the nozzle H, and of such length as to permit the device to swing forward and backward while the spout is in said slot 13.

The lower part of the forwardly projecting portion of the head formed by the mem-

- bers 9, 10 and 11 is open, that is,—no bottom is provided therefor, forming a vertical opening extending entirely through the head below the forward portion of slot 13. The 5 front 3 extends upwardly beyond the lower edges of the members 9 and 10, and it curves slightly forward, forming the lip 14, and with its ends permanently secured to the members 9 and 10.
- 10 Located slightly above and forward of the lip 14, and positioned at approximately the same angle as the lip 14, is the cut-off lip 15, it being suspended, with its ends permanently secured to the members 9 and 10 and 15 extending therebetween.
- Numerals 16 and 17 denote two offset lugs, each having an aperture 18 in its rear portion for the respective bolts C, and an aperture 19 in its forward portion for the respective pivots 7 and 8. Said lugs 16 and 17 are secured on the forward bolts C by means of the nuts D from which they extend forward. The pivots 7 and 8 are adapted to fit loosely in the respective apertures 19. 20 Numerical 20 denotes a flat spring, whose lower end is secured to the base B, from which it extends upward at an angle with its upper portion slidably engaging with the back 4 of the container.
- 25 *Modus operandi:* In actual practice we have the parts denoted by letters already in position substantially as shown. Now in order to place my device in connection therewith one has only to remove the two forward 30 nuts D and then place one of the lugs 16 and 17 on the bolts C and then replace the nuts D. Before the nuts D are finally tightened the lugs should be turned until the apertures 19 are spaced apart such as to receive the 35 pivots 7 and 8.
- 40 Then to place the device in position one has only to bring the device up to cause the nozzle H to enter the slot 13, then enter the pivots 7 and 8 in the respective apertures 19, and the device will be ready for use.
- 45 When it is desired to draw oil one has only to place a vessel under the projection of the head, that is under the parts 9 and 10, then press back, which will position the nozzle at 50 the front of the slot 13, as shown in Fig. 2, thereby permitting an unobstructed flow of oil from the nozzle into the vessel. Now if 55 the vessel be removed it is evident that the device will tip forward whereby the nozzle will be over the lip 15 and therefore the drip will be conducted into the container.
- I have found in practice that oil may 60 lodge on the edge of the lip 15 and if this occurs then the oil will run down on the outside of the lip 15 and then fall onto the lip 14 and then be conducted back as before. By reason of providing a plurality of lips as 65 the lips 14 and 15, I have absolutely provided against any oil running down on the outside of the container.

Also it should be observed that the stream of oil flowing from the nozzle into the vessel, and also the drippage following the withdrawal of oil, is absolutely shielded from the action of wind, thereby preventing the oil from being blown to one side.

When desired the container may be lifted up, to release the pivots 7 and 8, moving the lower end of the container forward, and then lowering the device to clear the nozzle H, 75 after which the device may be emptied of the oil contained therein, after which the device may be placed in operative position as before.

In practice the device will automatically 80 tip forward to its limit by gravity whenever it is released and without the aid of the spring 20, but in order to make the movement more positive and of less duration the spring 20 may be provided as shown. 85

It should be observed that by reason of the shape of the forward portion of the device, that is the lips 14 and 15 being forward of the front edge of the container, that when one starts to remove the vessel into 90 which oil is being conducted from the nozzle, that the lip 15 will cut off the oil before the vessel is entirely removed, therefore the oil will not be able to flow or drip onto the edge or side of the vessel, it being understood 95 that the device is to be tipped back by pressing against its upper portion with the said vessel.

I desire that it be understood that various 100 changes may be made in the several details of construction from that herein shown and described, and in the arrangements of the several parts, without departing from the spirit of the invention and without sacrificing any of the advantages thereof. 105

Having now fully shown and described my invention, what I claim and desire to secure by Letters Patent of the United States, is—

1. In combination with an oil dispenser 110 having a discharge nozzle, an oil container, a head integral with the upper portion of the container, there being a slot in the upper portion of the head in which the lower portion of the nozzle is located, the bottom of the overhanging portion of the head being open, a lip formed integral with the upper end of the container and adjoining said opening in the head, and a cut-off lip located above and projecting outward beyond 115 the first mentioned lip to catch the drip from the nozzle and conduct it to the base of the first lip by which it is conducted into the container, substantially as set forth.

2. In combination with an oil dispenser 120 having a discharge nozzle, an automatic oil drip catcher comprising a container for oil, means for pivoting the lower portion of the device whereby the upper portion may swing forward and backward limited by en-

- gaging with said nozzle, and means carried by the upper portion of the device for catching dippage from the nozzle when the device swings forward, the flow from the nozzle being adapted to enter directly into a vessel distinct from the device when the device is swung rearward.
3. In combination with an oil dispenser having a nozzle, an oil container removably pivoted at its lower portion, a head integral with the upper portion of the container with the lower portion of said nozzle located in the head, and means whereby when the container swings back to its limit the oil from said spout may pass through the head into a vessel located therebelow and when the vessel is removed the device will automatically tip forward and cause the nozzle to drain into the container.
4. In combination with an oil dispenser having a fixed discharge nozzle directed downward, an oil container removably hinged at its lower portion, a head integral with the upper portion of the container with the lower portion of said nozzle projecting into the head and adapted to limit the movements of the device upon its hinges, and a lip for cutting off the oil from the nozzle and conducting it into the oil container, substantially as set forth.
5. In combination with an oil dispenser having a fixed nozzle, a container hinged
- at its lower end, a head integral with the upper end of the container and having an opening formed vertically therethrough into which the lower portion of the nozzle is disposed, a lip formed by the upper portion of the container and adjoining said opening in the head, and a cut-off lip located above the first named lip and adapted to receive drip-page from the nozzle and conduct it into the container, substantially as set forth.
6. In combination with an oil dispenser having a fixed nozzle, a container hinged to swing forward and backward, a head integral with the upper end of the container and having an opening formed vertically therethrough into which the lower portion of the nozzle is disposed, means carried by the upper portion of the device for catching dippage from the nozzle when the device swings forward, the flow from the nozzle being adapted to enter directly into a vessel distinct from the device when the device is swung rearward, and spring means for positively swinging the device forward whenever the device is released.

In testimony whereof I have hereunto subscribed my name to this specification in the presence of two subscribing witnesses.

MICAJAH C. HENLEY.
